(57) CLAIM

The ornamental design for business suit for physically challenged, as shown and described.

DESCRIPTION

FIG. 1 is a front plan view of a business suit for physically challenged showing my new design;

FIG. 2 is a rear plan view thereof;

FIG. 3 is a front left perspective view thereof;

FIG. 4 is a front right perspective view thereof;

FIG. 5 is a rear left perspective view thereof;

FIG. 6 is a rear right perspective view thereof;

FIG. 7 is a left side plan view thereof;

FIG. 8 is a right side plan view thereof;

FIG. 9 is a top plan view thereof; and,

FIG. 10 is a bottom plan view thereof.

The broken line showing the environment is for illustrative purpose only and forms not part of the claimed design.
